UNITED STATES PATENT OFFICE.

HENRY B. CONNERS, OF SIOUX CITY, IOWA.

HINGE.

1,079,215.

Specification of Letters Patent.

Patented Nov. 18, 1913.

Application filed November 21, 1912. Serial No. 732,756.

To all whom it may concern:

Be it known that I, HENRY B. CONNERS, a citizen of the United States, residing at Sioux City, in the county of Woodbury and State of Iowa, have invented new and useful Improvements in Hinges, of which the following is a specification.

The present invention has reference to improvements in hinges, and it comprehends, briefly, a combined strap and butt hinge which is so constructed as to offer, when attached to a door frame and door, the maximum resistance to the weight of the latter or to any pressure exerted thereagainst.

15 The improved hinge is constructed in such manner that the butt hinge members or leaves are cut from and located intermediately of the strap members or leaves and the knuckles of the several leaves are so formed 20 on the respective leaves as to aline for movable association through the medium of a single pintle, and said knuckles are also disposed in such manner relatively to their respective leaves as to materially increase the 25 strength of the hinge organization at the points of assemblage of the leaves by supporting and reinforcing each other as well as more uniformly equalizing the strain or weight tension of the door over all of the 30 knuckles and different portions of the pintle.

An embodiment of the invention is illustrated in the accompanying drawing, whereof:

Figure 1 is a fragmental view of a door frame and door connected by the improved hinge, the door being shown as partly closed; Fig. 2 is an enlarged horizontal section taken on the line 2—2 of Fig. 1, showing the door both as partly closed and as fully closed, the latter position being indicated by dotted lines; and Fig. 3 is a perspective view of the hinge itself.

As shown in said drawing, the hinge embodies pairs of main and supplemental members or leaves 5, 6 and 7, 8, all of which parts are provided with knuckles, as hereinafter described, for the reception of a single pintle 9. Each supplemental leaf is produced by cutting or stamping out a section from the inner central portion of the main leaf 5 or 6, or if desired all four leaves may be stamped or cut out from a blank at a single operation, there being no waste metal resulting from the construction of the leaves from the blank. The two supplemental leaves 7 and 8 are substantially rectangular

in contour, and the two main leaves 5 and 6 are materially larger than the supplemental leaves and are approximately C-shaped with their open portions disposed inwardly toward the pintle. The knuckles of the several leaves are located in a particular manner to give the best results from a standpoint of operative association as well as strength and durability, and are contributory as a whole in the distribution of the weight strain over different portions of the pintle and also relatively to each other. The knuckles 10 and 11 of the supplemental leaf 7 are respectively formed at the upper and lower extremities of the inner portion of said leaf and have their respective upper and lower ends coincident with the upper and lower ends of the said leaf, whereas the leaf 8 has a single intermediate knuckle of elongated form at its inner edge to fit in between the knuckles 10 and 11, the distance between the upper and lower ends of the knuckle 12 and the upper and lower edges of the leaf 8 being precisely equal to the length of the knuckles 10 and 11, and the upper and lower portions of the inner portion of the leaf 8 are recessed to receive the knuckles 10 and 11 of the leaf 7. The main leaf 5 has knuckles 13 and 14 formed at the inner edge thereof terminating coincidently with the upper and lower edges of the inner opening of said leaf, the upper and lower edges of the knuckles 13 and 14 terminating respectively at a distance inwardly from the upper and lower ends of the leaf 5 so as to form seats for knuckles 15 and 16 located at the upper and lower portions of the leaf 6, the respective upper and lower ends of the knuckles 15 and 16 terminating coincidently with the upper and lower edges of the said leaf 6. It will be seen that when the knuckles as just explained are associated in longitudinal alinement, the pintle 9 may be readily inserted therethrough, and the knuckles 13 and 14 of the leaf 5 are respectively supported on the knuckle 10 of the leaf 7 and the knuckle 16 of the leaf 6, whereas the knuckles 10, 11 and 12 of the leaves 7 and 8 are held between the knuckles 13 and 14 of the leaves 5 and 6 to form a very rigid support and a strong intermediate connection through the medium of leaves 7 and 8 between the door and frame. The knuckles 13, 15 and 14, 16 of the leaves 5 and 6 support the pintle ends and embrace a considerable portion of said pintle ends to

provide a positive end reinforce and thereby give the central portion of the pintle a more rigid resistance against bending by the weight strain of the door concentrated thereon through the leaves 7 and 8. A light weight hinge of economical structure can thus be used to do heavy work.

In associating the members of the hinge, the knuckles 10, 11 and 12 of the leaves 7 and 8 are assembled or the leaves have their inner ends disposed in normal positions, and the knuckles 13, 14, 15 and 16 of the leaves 5 and 6 are likewise normally positioned and the knuckles 10, 11 and 12 then inserted between the knuckles 13 and 14, and the pintle 9 is finally passed through all of the knuckles, thus leaving the leaves 7 and 8 free to move between the leaves 5 and 6. It will be seen that the leaves 7 and 8 are of similar dimensions and likewise the leaves 5 and 6.

To attach the hinge, the main leaves 5 and 6 are affixed by screws 17, or the like, to the front or outer faces of the door frame 18 and door 19, respectively, and the supplemental leaves 7 and 8 are similarly fastened by the screws 20, or other devices, to the side or edge faces of said frame and door, the arrangement of parts being obviously such that each main leaf is disposed at right angles to its companion supplemental leaf, and its screws 17 at right angles to the screws 20. It will be seen, therefore, that the leaves 7 and 8 form what may be considered a butt hinge and the leaves 5 and 6 constitute a strap hinge, the two hinges being connected by the pintle 9, which is common to both, so that the resultant structure presents the combined advantage of both forms of hinge. By reason of the specified arrangement of the fastenings 17 and 20 it will be apparent that both sets of fastenings sustain the weight of the door and the tendency to loosen either set by the pulling strain imposed thereon is offset or prevented by the corresponding set at right angles thereto or at right angles to the direction of the weight strain of the

door. By making the knuckles on the main leaves of half-length, and reversely arranging them, the requisite movements of the door are permitted without interference on the part of the knuckles, and the cost of manufacture is lessened since no vertical bending of the arms is necessary to offset the knuckles. Finally, an initial individual adjustment of all of the leaves is obtainable, owing to their mounting upon a common pintle, and the hinge, as a whole, thus rendered attachable to doors and door frames of various shapes and dimensions.

I claim:—

A hinge comprising two strap leaves of equal dimensions having upper and lower knuckles, two butt hinge leaves consisting of rectangular sections of the same size cut from the intermediate portions of the strap leaves and having knuckles at their inner portions, the knuckles of the one butt hinge leaf being at the upper and lower ends of the leaf and the other butt hinge leaf having a single knuckle at the inner edge between the ends thereof to fit between the end knuckles of the other butt hinge leaf, the knuckles of the butt hinge leaves being held between the innermost knuckles at the upper and lower ends of the strap leaves, the two sets of knuckles being disposed in vertical alignment, and a single pintle inserted through and connecting the knuckles of all the leaves, the strap leaves and the butt hinge leaves being movable independently of each other on the pintle, the knuckles of both pairs of leaves supporting each other and operating to distribute the weight strain imposed on the leaves equally over different portions of the pintle to avoid intermediate bending of the pintle.

In testimony whereof I have hereunto set my hand in presence of two subscribing witnesses.

HENRY B. CONNERS.
